UNITED STATES PATENT OFFICE.

STEPHEN OLOP, OF DENVER, COLORADO, ASSIGNOR OF ONE-THIRD TO AUSTIN L. CUNNINGHAM, OF ST. PAUL, MINNESOTA.

SAFETY PIN.

Application filed February 16, 1920, Serial No. 359,144. Renewed July 6, 1922. Serial No. 573,190.

To all whom it may concern:

Be it known that I, STEPHEN OLOP, a citizen of the United States, resident of Denver, in the county of Denver and State of Colorado, do, have made a certain new and useful Invention in Safety Pins; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the invention.

Figure 2 is a plan view of the same.

Figure 3 is a side view of the same.

Figure 4 is a detail cross section through the coil housing.

Figure 5 is a similar view of the housing for the point of the pin.

Figure 6 is a perspective view of a modification of the invention wherein the outline is elliptical.

Figure 7 is a detail section showing a coil housing of seamless form.

Figure 8 is a similar view of a seamless housing for the point of the pin.

The invention has relation to safety pins and particularly to such pins having side bars constituting a frame, and a pin located centrally of said side bars and provided with a resilient end coil serving to move the pin outwardly away from said side bars when the former is released from its guard or housing, said coil located substantially at right angles to the plane of the side bars or in a plane angularly disposed to and intersecting the plane of the side bars, the object being to reduce the projection of the coil beyond the plane of the side bars upon the face of the device occupied by the pin proper, whereby the side bars or frame of the pin is adapted to lie close to the goods or garment, being not held away from said goods or garment by an end coil the major portion of which lies upon the inner side of said side bars. Other objects and advantages will hereinafter appear.

In the accompanying drawings illustrating the preferred embodiment of the invention, the numeral 2 designates parallel side bars constituting the back or frame of the pin said bars connected at one end by bar

3 one of said bars 2, being formed at its other end into a coil 4 which may be disposed in a plane nearly or substantially at right angles to the plane of the side bars, but is preferably arranged aslant or having its axis oblique to the plane of the side bars, as shown in Figures 4 and 7, a pin 5 projecting from the upper terminal of said coil parallel to the side bars and located centrally therebetween.

Preferably the end-coil 4 is so arranged that it projects above and below the side-bars and, as shown, the side-bars being assumed to lie in a horizontal plane, the said end-coil 4 projects above and below said plane to an equal extent, substantially.

A housing 6 for the coil 4 has a dished bottom 7, and a reversely dished top 8, which also respectively project downwardly and upwardly above and below the plane of the side bars to an equal extent.

A housing 9 for the point of the pin likewise has a dished bottom 10 and a reversely dished top or guard 11 respectively projecting below and above the plane of the side bars to a similar or equal extent.

The side of the safety pin bearing the pin proper is the inner side, which lies adjacent to the garment or goods, and it will be obvious that by sinking the end coil between the side bars so that it will project equally thereof at the inner or garment side and at the outer side, the frame of the pin or the pin as a whole will be brought as close to the garment or goods as is consistent with a well balanced pin, which will prevent any appreciable pivotal movement or rocking of the pin frame upon the pin proper as a center when the latter is engaged with the goods. The housing for the end coil lies close thereto and these advantages are retained, said housing being made with lateral members 12 bent inwardly at 13, around the side bars and extending inwardly thereof, and with an end member 14 reversely bent or bent upon itself to form the top or guard, the latter having lateral extensions 15 located between the dished bottom 7, and the inward projections 13, being clamped in such position when the metal is stamped or die struck.

The housing for the point of the pin projecting as stated equally above and below or at each side of the plane of the side bars is provided with lateral members 16 bent inwardly over the side bars at 17 and extend-

ing thence parallel to the dished bottom close thereto at 17' and having terminal bends 18 extending outwardly or between the side bars centrally thereof to form a ridge 19, which 5 terminates at a point just beyond or nearly in line with the side bars. This housing has an end member 20 which is bent reversely to form the guard or top, reversely dished over the aforesaid ridge, the point of the 10 ridge being substantially concentric of the concavity of the said top and spaced apart therefrom and also spaced from the extensions 17' to admit the point of the pin, the sides of said dished top being spaced apart 15 at 21 from the inward bends 17, to form passages 22 for entrance and exit of the pin point.

These housings may also be made seamless, as illustrated in Figures 7 and 8, by 20 means well known in the art.

The pin is connected to the coil by a bend, in order to provide a working clearance between the pin and edge of the housing.

This bend permits the forward edge of 25 the housing to be brought down nearer to the plane of the side-bars, thereby reducing the tendency of being caught by or engaging with materials brought into contact with the safety-pin in use.

30 The slanting position of the coil imparts to the piercing-pin 5, in addition to the main resiliency in an upward direction away from the plane of the side-bars, a sufficient lateral resiliency to enter the housing for the pin-point automatically when placed opposite one of the side-passages 22, thereby enabling 35 the safety-pin to be more readily manipulated by one hand. It, moreover, permits the housing to be made flatter and hence to project less above the material to which the pin is attached.

As best shown in Fig. 3, the said bend is first downward below the edge of the housing 6 and then upward. This downward and 45 then upward bend permits the pin to be properly spaced with relation to the side-bars to allow the fabric intercepted by the said side-bars to lie flat and at the same time to afford said working-clearance and to permit the edge of the housing to be brought down low enough to avoid a tendency to engage with or to be caught in articles brought 50 in contact with the pin-attachment.

I claim:

55 1. In a safety-pin, a frame comprising two side-bars and a resilient pin arranged between said side-bars and hinged to the frame by a coil, in combination with a housing at one end of the frame and comprising a catch for the pin-point, the bottom of said housing being dished away from the frame.

60 2. In a safety-pin, a frame comprising two side-bars and a resilient pin arranged between said side-bars and hinged to the frame by a coil and extending above and

below the frame, in combination with a housing at one end of the frame and comprising a catch for the pin-point, the bottom of the housing extending below the plane of the frame, and a housing at the other end 70 for the coil, the bottom of said housing also extending below the plane of said frame.

3. In a safety-pin, a frame comprising side-bars and a pin arranged between said side-bars, in combination with a spring connecting the pin to the side-bars, said spring being arranged obliquely with respect to the side-bars, and a housing for the pin. 75

4. In a safety-pin, a frame comprising side-bars and a pin arranged between said side-bars, in combination with an end-coil connecting the pin to the side-bars, said coil being arranged obliquely with respect to the plane of the side-bars, and a housing for the pin. 80

85 5. In a safety-pin, a frame comprising side-bars, an end-coil extending below the plane of said side-bars, and a pin extending from said coil and arranged between said side-bars, in combination with a housing for the coil projecting below said plane, and a housing for the pin-point also extending below said plane. 90

95 6. In a safety-pin comprising side-bars and an intermediate piercing-pin spring-hinged at one end of the side-bars, a housing for the said end of the side-bars consisting of sheet material dished downwardly with respect to the plane of the side-bars, and having lateral members bent over the side-bars inwardly, and extending inwardly beyond the side-bars and an end-member bent over the top of the side-bars, its lateral edges being bent downwardly and outwardly and under the inwardly extending part of the lateral members. 100

105 7. In a safety pin comprising side-bars and an intermediate resilient piercing pin, a housing for the point of the pin formed of sheet material, having lateral members bent over the side bars, and extending inwardly, the ends of said lateral members being bent upwardly at a point between the side-bars to form an upward projection or ridge, and an end-member bent reversely over said projection or ridge to form a pin-guard, said pin-guard being spaced apart from the ridge and the inward extensions of the lateral members to form passages for the pin point. 110

115 8. In a safety-pin comprising side-bars and an intermediate resilient piercing-pin, a housing for the point of the pin formed of sheet-material dished downwardly with respect to the plane of the side-bars, and having lateral members bent over the side-bars inwardly, the ends of said lateral members being bent upwardly at a point between the side-bars to form an upward projection or ridge, and an end-member bent reversely over said projection or ridge to form a pin- 120

125

130

guard, said guard being spaced apart from the ridge and from the inward extensions of the lateral members to form passages for the pin-point.

5. 9. In a safety-pin comprising side-bars and an intermediate piercing-pin, a coiled spring connecting the pin to the side-bars and a housing for the coiled spring, the said coiled spring being connected to the pin by

a downward and then upward bend, to provide a working clearance for the pin with respect to the housing. ¹⁰

In testimony whereof I affix my signature in presence of two witnesses.
